UNITED STATES PATENT OFFICE.

WILLIAM J. FRISBIE, OF CHICAGO, ILLINOIS, ASSIGNOR TO JUSTRITE MANUFACTURING COMPANY, OF CHICAGO, ILLINOIS, A CORPORATION OF ILLINOIS.

LAMP-HOLDER.

1,349,566.

Specification of Letters Patent. Patented Aug. 17, 1920.

Application filed May 3, 1920. Serial No. 378,414.

To all whom it may concern:

Be it known that I, WILLIAM J. FRISBIE, a citizen of the United States, and a resident of Chicago, in the county of Cook, 5 State of Illinois, have invented certain new and useful Improvements in Lamp-Holders, of which the following is a specification.

My invention relates to lamp holders, particularly to holders which can be conveniently and detachably stuck or driven into cracks, crevices or soft material to form a support and which is provided with means for adjustably supporting miners acetylene lamps thereon.

Miners frequently find it desirable to support their cap lamps from a wall, post or other structure in mines. There are devices of this class in the prior art, but they are all more or less impractical, unreliable 20 and expensive to manufacture, and do not efficiently support lamps. Among the important objects of my invention are: to provide a holder in the form of a pin which can be readily stuck into cracks or soft material and driven into harder material; to provide an improved frame detachably applicable to said pin into which a lamp can be readily inserted to be securely held to the pin; to provide an arrangement which will 25 cause the frame to become automatically locked to the pin when the lamp is inserted; to provide an arrangement which will permit free rotational movement of the lamp while being securely held on the pin; to provide an arrangement which will permit the 30 pin to serve as a carrying handle for the lamp when the pin is detached from its support; to provide a pin with a wedge-shaped insertion end and means for permitting application of the supporting frame to 35 the pin so that the lamp can be supported on any side of the pin; to provide a supporting frame which can be constructed from a single piece of wire; and in general 40 to provide a supporting structure of the class referred to which is simple, strong and efficient and which can be inexpensively manufactured.

The above and other features of my invention are incorporated in the structure shown on the accompanying drawing, in which drawing—

Figure 1 is a side elevational view of the holder applied to a supporting wall and 55 having a lamp mounted thereon,

Fig. 2 is a plan view of the holder with the lamp removed,

Fig. 3 is a sectional view on plane 3—3, Fig. 1,

Fig. 4 is an enlarged sectional view on 60 plane 4—4, Fig. 1,

Fig. 5 is a similar sectional view showing a modified locking arrangement and

Fig. 6 is also a similar sectional view showing another modified form of locking 65 arrangement for the frame on the pin.

The pin P is formed on a single length of preferably steel bar of polygonal cross section, the pin shown being of rectangular cross section. One end of the pin is forged 70 or otherwise formed down to form a sharp wedge-shaped end 10, while the other end of the pin is bent to form the circular head 11. Intermediate its ends the pin has a number of holes 12 and 12' drilled therethrough and extending alternately in opposite direction at right angles with the opposite side of the pin. The lamp supporting frame F is bent up from a single piece of wire tempered to the suitable springiness. 75 The frame has the middle or upright section 13 and the upper horizontal section 14, this upper section being bent to form an open ring of approximately 270 degrees extent, the end 15 being bent out slightly and the bend 16 being rounded so that a lamp can readily be inserted into the ring between the end and the bend, the diameter of the ring being such as to readily receive a miner's lamp L around its cylindrical 80 waist 17, as clearly shown in Fig. 1, the ring being normally slightly contracted so that when the lamp is applied, it will be clamped by the ring but will be free to be rotated therein under slight force applied to the 85 lamp.

At its lower end, the wire frame is bent laterally in the direction of the open end of the ring 14 to form the side loop 18, and beyond this side loop the wire is bent 90 horizontally in the opposite direction to form the section 19, then inwardly in the direction of the ring and slightly inclined downwardly to form the section 20, and then laterally in the direction of the open end of the ring to form the horizontal end section 21. This end 21 is inserted through one of the horizontally extending openings 12, and the section 19 is brought against the top of the pin, the section 20 being suffi- 95 100 105 110

ciently slanted so that when in this position the ring 14 of the frame will be horizontal. When the lamp is now inserted into the ring it will seat on top of the pin, and the distance between the pin and the ring is such that the frame will be strained sufficiently when the lamp is inserted to exert slight downward pressure which serves to hold the lamp rigidly against the pin to prevent rattling thereof. The lamp is however free to be rotated into any position on the pin by a slight rotative effort thereon and the clamping engagement of the frame on the lamp and between the frame and pin will hold the lamp in any position to which it has rotated. The upper part 13' of the upright section 13 is slightly inclined or bent so that the frame will be cleared by the reflector R of the lamp which will enable the lamp to be turned entirely around without ever striking the frame. The wire frame can be first applied to the lamp and then both the frame and the lamp applied to the pin, or, the wire frame can first be applied to the pin and the lamp then forced into the ring 14.

Ordinarily, the clamping engagement of the frame with the lamp will hold the lamp to the pin, but miners are more or less rough in handling devices of this kind so that I preferably provide means for locking the frame to the pin to prevent accidental disconnection. One arrangement for locking the frame is shown in Fig. 4. Here, the lower limb of the loop 18 is deflected downwardly a distance to form the bead or rounded ridge 22 which, when the wire frame is applied, engages with the side of the pin opposite to the side from which the end 21 is inserted through the pin. When the lamp is applied in the supporting frame, engagement of the bead with the pin will be maintained and the wire frame is securely locked against accidental displacement. The bead is however made sufficiently short and gradual that under exertion of lateral pressure against the frame it will spring sufficiently to permit removal of the frame before the lamp is removed therefrom and likewise, to permit the frame and lamp to be simultaneously applied to the pin. The bead will however, insure against accidental displacement of the wire frame after application.

In Fig. 5 an arrangement is shown with which the wire frame must be applied first to the pin and the lamp inserted afterward. Here the loop 18 has the more pronounced extension 23 which has extended engagement with the side of the pin. With this arrangement the lamp must be removed from the frame before the frame can be withdrawn from the pin.

In Fig. 6 still another locking arrangement is shown. Here, the end of section 21

is threaded to receive a nut 24 and with this arrangement, like with the arrangement in Fig. 5, the frame must be applied to the pin before the lamp is applied, and the lamp must be withdrawn from the frame before the frame can be released from the pin. 70

The circular head 11 affords a convenient means for carrying the holder and lamp when the holder is withdrawn from a support, and when the pin has been fastened to a support, this circular ring also serves as a support on which things can be hung. 75

The pin is usually applied by inserting its flat wedge-shaped end into a crack, or by driving it into softer material such as wood, coal or earth. Sometimes horizontal cracks or fissures are available but other times only vertical fissures or cracks are available and it is for this reason that I extend some of the holes 12 in one direction through the pin and other holes 12' in directions at right angles. The pin can be readily accommodated for application in available cracks by inserting the frame into one or another of the available holes through the pin. As the pin is of steel it possesses great strength and can be driven into a support to be securely held. 80

As the entrance ends of the ring 14 are well rounded and round wire is preferably used for the frame, the lamp which is usually constructed of softer material such as brass, will not be injured during application to the frame or during adjustable rotation on the holder. 90

I thus provide a very simple, strong and efficient holder structure. The pin can be inexpensively bent up from a single length of stock material and likewise the holder frame can be inexpensively formed from a single piece of wire. I do not, of course, desire to be limited to the exact construction, arrangement and operation shown and described as modifications are possible 95 which would all come within the scope of my invention. 100

I claim as follows:

1. In a lamp holder of the class described, the combination of a pin having a hole therein, a frame having a laterally extending end section and a laterally extending intermediate section for engaging respectively in said hole and on said pin, the upper end of said frame being formed to span a lamp 115 at an intermediate part thereof to thereby hold said lamp on said pin. 120

2. In a lamp holder of the class described, the combination of a pin having a hole, a frame formed of a single piece of wire and 125 having its lower end deflected to engage in said hole, the upper end of said frame being bent to form a loop, said frame adjacent its lower end being deflected to seat against the top of said pin to hold said loop in hori- 130

zontal position over said pin, said loop serving to receive a lamp and hold it against the top of the pin.

3. In a lamp holder of the class described, the combination of a pin having a hole, a frame formed of a single piece of wire and having its lower end deflected to engage in said hole, the upper end of said frame being bent to form a loop, said frame adjacent its lower end being deflected to seat against the top of said pin to hold said loop in horizontal position over said pin, said loop serving to receive a lamp and hold it against the top of the pin, and a projection at the lower end of said frame for abutting against said pin when said loop is in horizontal position to prevent removal of said loop from said pin.

4. In a lamp holder of the class described, the combination of a pin having a hole, a frame bent from a single piece of wire and having its lower end deflected to engage in said hole, the upper end of said frame being deflected and bent to form a loop, said frame adjacent its lower end being deflected to form an abutment section for engaging against the top of the pin to hold said loop in horizontal position over said pin, said frame at the end of said abutment section being deflected downwardly to form an abutment for engaging against the side of the pin to prevent removal of said frame from the pin when said loop is in horizontal position, said loop serving to receive a lamp intermediate its ends and to clamp said lamp and hold it on the top of said pin.

5. In a lamp holder of the class described, the combination of a pin having a plurality of holes extending in different directions

transversely therethrough, a holder having 40 a projection at its lower end for removably and selectively engaging in said holes to swing vertically, a loop at the upper end of said holder, a seating section on said frame for engaging against the top of said pin to 45 prevent upward swing of said loop beyond horizontal position, said loop serving to receive a lamp and to hold the lamp against the top of said pin.

6. In a lamp holder of the class described, 50 the combination of a pin having a plurality of holes extending in different directions transversely therethrough, a holder having a projection at its lower end for removably and selectively engaging in said holes to 55 swing vertically, a loop at the upper end of said holder, a seating section on said frame for engaging against the top of said pin to prevent upward swing of said loop beyond horizontal position, said loop serving to 60 receive a lamp and to hold the lamp against the top of said pin, said loop permitting rotation of said lamp on said pin.

7. In a lamp holder of the class described, 65 the combination of a pin having a hole extending transversely therethrough, a holder having a projection at its lower end for engaging in said hole whereby said holder may swing vertically, a loop at the upper end of said holder for receiving a lamp and for 70 holding it on top of the pin, said holder having a projection for engaging with the side of the pin when a lamp is received in the loop, said projection preventing escape of said holder from said hole. 75

In witness whereof, I hereunto subscribe my name this 30th day of April A. D., 1920.

WILLIAM J. FRISBIE.
